UNITED STATES PATENT OFFICE.

LENA M. HOFFMAN, OF PHILADELPHIA, PENNSYLVANIA.

BED-PAN.

SPECIFICATION forming part of Letters Patent No. 727,949, dated May 12, 1903.

Application filed January 7, 1902. Serial No. 88,759. (No model.)

To all whom it may concern:

Be it known that I, LENA M. HOFFMAN, a citizen of the United States, residing in the city and county of Philadelphia, State of Pennsylvania, have invented a new and useful Improvement in Bed-Pans, of which the following is a specification.

My invention consists of a bed-pan which may be heated or cooled according to requirements, and is provided with a cover for preventing escape of odors and which may be removed in order to empty, clean, and disinfect the pan, it being also adapted to electrically charge the occupant of the pan and, furthermore, adapted to subject a patient to hot or cold treatment, and is generally serviceable for family, gynecological, hospital, doctors', and nurses' purposes.

Figure 1 represents a top or plan view of a bed-pan embodying my invention. Fig. 2 represents a central longitudinal vertical section thereof. Fig. 3 represents a transverse section on line *y y*, Fig. 1. Fig. 4 represents a view of an electrode that is adapted to be connected with the pan. Fig. 5 represents an end view of a portion.

Similar letters of reference indicate corresponding parts in the figures.

Referring to the drawings, A designates a bed-pan, which consists of the body B, the lid C, and the removable top C', in which said lid is fitted. On the upper end of the body is the cross-bar D, and on the adjacent portion of the top C' is the open ear E, which may be hooked under said bar and form a hinge for said lid, while by raising the top and manipulating the same so that the ear may be withdrawn from under the cross-bar D the members of the hinge are separated and the top may be removed from the body when so required for purposes of full access to the interior of the latter. When the pan is to be used, the lid C is removed and the flanged wall of the cover of the top C' constitutes the seat. When the use is accomplished, the lid is restored in position, its depending flange engaging with the flange of the opening in said top or cover C', thus completely

closing the pan, when the latter may be carried elsewhere without escape of odors there- 50 in, and the top and lid may be removed for cleansing, disinfection, &c.

In one end of the body B—in the present case the lower end—there is a socket F, the same being adapted to guide an electrode G 55 into the socket H in the depending rim or flange J of the top C', so that the occupant of the pan may be electrically treated when so desired. In this case the patient grasps the handle of the other electrode, both electrodes 60 leading from a source of electrical supply, thus forming the current.

The body may be made of metal or other material, enameled or otherwise coated, and may receive hot water, steam, or other heat- 65 ing medium, or the electrode may be in communication with a heating device within the pan, or the pan may receive ice or other cooling medium, so that in either case the patient may have hot or cold treatment, according to 70 requirements.

The lid C is flat and conforms to the shape of the top C', so as to avoid material projection of the parts, and the handle K of said lid when not in use occupies the recess L, so 75 as to be sunken and placed out of the way.

It will be seen that the removable top C', the lid C, and the top wall of the recess L form an unbroken flat slope from the one end of the pan to the other, and said recess L 80 prevents the handle K when folded therein from projecting above the lid, and thus when the cooling or heating material is placed in the pan it will cool or heat the lid and top, and the patient may be seated or rested on 85 the pan, and so be subjected to the cold or hot treatment while contacting with a flat surface and without any projecting parts.

Having thus described my invention, what I claim as new, and desire to secure by Letters 90 Patent, is—

1. A bed-pan consisting of a body, a removable cover having an open seat thereon, a removable lid on said seat adapted to cover the opening therein and having a socket thereon, 95 a detachable hinge connection between the

cover and body for locking the cover to the body, a socket on the body and a removable electrode to engage said sockets.

2. A bed-pau consisting of a body, a removable cover having an open seat thereon, a removable lid on said seat adapted to cover the opening therein, a detachable hinge connection between the cover and body for locking

the cover to the body, a socket in the body at the end opposite the hinge, and a removable electrode to engage said socket to lock and support the end of the cover.

LENA M. HOFFMAN.
